UNITED STATES PATENT OFFICE

RALPH P. KIPP, OF OSSINING, NEW YORK

BLOOD TRANSFUSION DEVICE

Application filed May 6, 1931. Serial No. 535,492.

This invention relates to surgical devices, and more particularly to a surgical device designed for use in the transfusion of blood, an important object of the invention is to 5 provide a device of this character which will measure the blood passing from the donor to the recipient, in such a way that the blood stream is subjected to the minimum of contact or disturbance, without mechanical injury to its constituents, by avoiding subjecting the blood to excessive suction, intense pressure, friction or impact, and having temperature maintained.

A further object of the invention is to provide a device to carry out the transfusion of blood in such a way that the rate of blood flow from the donor to the recipient may be observed and controlled, and the air suction and pressure which respectively provide the 10 above effects, are maintained uniform, accurately observable, and instantly adjustable, and that the cycle of transfusion is quickly effected with practically no effort on the part of the operator.

Another object of the invention is the provision of a device wherein the parts in blood contact are few, simple, easily taken apart for sterilization and coating with paraffin.

A still further object of the invention is to provide a machine which is portable, silent in operation, and one which is particularly adapted for accomplishing the purpose for which it has been invented.

With the foregoing and other objects in view, which will appear as the description proceeds, the invention resides in the combination and arrangements of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a sectional view through a blood transfusion device, constructed in accordance with the invention.

Figure 2 is a sectional view taken at right angles to Figure 1.

Figure 3 is a plan view of the device, the cover thereof having been removed.

Figure 4 is a sectional view taken on line 4-4 of Figure 3.

Figure 5 is a sectional view through the 55 valve that controls the passage of air to and from the tank, showing the valve in its neutral position.

Figure 6 is a similar sectional view, and illustrating the valve in a position to cause a 60 vacuum to be created in the tank.

Figure 7 is a sectional view through the valve, illustrating the valve in a position whereby pressure will be created in the tank, forming a part of the device. 65

Figure 8 is a sectional view taken on line 8-8 of Figure 4.

Figure 9 is a sectional view taken on line 9-9 of Figure 4.

Figure 10 is a fragmental sectional view of the main valve, taken on line 10-10 of Figure 4.

Referring to the drawings in detail, the device comprises a base indicated generally by the reference character 5 and on which the mechanism constituting the surgical device, is supported. 75

The reference character 6 designates an electric motor, which is supplied with suitable gearing not shown, for operating the pump indicated by the reference character 7. The pump includes a piston 8 and piston rod 9, which is eccentrically connected to the wheel 10 of the gearing, as at 11. Disposed at one end of the pump 7, is a block 12 which is provided with an upper passageway 13 and a lower passageway 14, the passageways 13 and 14 adapted to register with the arcuate grooves 16 and 17 respectively, formed in the valve member 18. This valve member 18 is rotatably supported within the housing 19, and is held into close engagement with the block 12, by means of the coiled springs 20, there being provided an operating lever 21, for operating the valve member 18, to control the passage of air through the passageways 13 and 14. 85

An opening 20' extends through the valve member 18 and is adapted to register with 90 100

the opening 13, when the mechanism is running idle.

As shown, by Figure 1 of the drawings, a filtering head 22 is provided, and is secured adjacent to the lower passageway 14, so that air drawn into the passageway 14 will be purified, before entering the measuring vessel of the device.

Supported within the block 12 and disposed on opposite sides of the passageways 13 and 14, are valve members 23 and 24 respectively. A passageway 28 is provided in the valve member 23 and extends through the valve member 23, the passageway being provided with a valve seat intermediate its ends, against which the ball valve 26 seats. A coiled spring 27 engages the ball valve 26 and normally acts to urge the ball valve 26 to its active position, to prevent the air pressure in the tank, from returning to the pump cylinder. This spring 27 is held in place by the threaded cap 28. The valve member 23 acts to control the action of the air as the air is being forced into the measuring vessel of the device, to be hereinafter more fully described.

The valve member 24 is provided with a passageway 29 that extends therethrough, there being provided a ball valve 30 for controlling the passage of air through the valve member 24. This ball valve 30 is held to its seat by means of the coiled spring 31 which in turn is held in position by the screw 32.

It will be obvious that the valve member 24 is so arranged that the suction created by the piston 8 will act to create a vacuum in the measuring vessel.

A combined vacuum relief valve and pressure relief valve forms a part of the device, and includes the body portion 34 formed with an extension pipe 33 through which the body portion 35 is in communication with the passageway 13.

The body portion 34 has bores 35 and 36 respectively, the bores 35 and 36 being provided with valve seats for the reception of the valves 35 and 39 respectively which are normally held to their seats by means of the coiled springs 40 and 41 respectively, that in turn are tensioned by the adjusting screws 41.

The bore 36 communicates with the atmosphere through the opening 38, the opening 38 being normally closed by the bore valve 39 which is held to its seat by the spring 40 and adjusting screw 41.

In order that the pressure in the measuring vessel or tank may be readily determined, a pressure gauge indicated at 42 is provided.

Communicating with the bores 35 and 36, is a pipe 43 that leads to the measuring vessel 44, that has its inner surface coated with paraffin and which is in the form of an inverted bottle having graduations provided thereon, to indicate the contents of the measuring vessel.

As clearly shown by Figure 2 of the drawings, the mouth of the measuring vessel or tank is removably held in the support 45 which in turn is formed with an extension 46 also removably fitted in the socket member 47, rising from the base 5. Extensions 48 and 49 respectively extend from the support 45, and to which the tubes 50 and 51 respectively are connected, the tube 50 leading to the donor of the blood, while the tube 51 leads to the recipient.

A valve 52 is mounted in an opening of the support, and is provided with an opening adapted to establish communication between either tube 50 or 51 and the measuring vessel, so that fluid may be drawn into the measuring vessel, through the tube 50, and exhausted therefrom, through tube 51.

Link 53 connects the valve and lever 21, so that movement of the lever 21, to set the valve member 18 for producing a vacuum or pressure in the measuring vessel, will cause a relative movement of the valve 52, to correspondingly set the valve 52.

An electric lamp indicated by the reference character 56 is mounted adjacent to the measuring vessel, to maintain the temperature of the blood, and make visible the level of blood within the measuring vessel.

Formed in the valve 18, is an opening 20' which is brought into registry with the passageway 13 to establish communication between the vessel and atmosphere to exhaust air from the vessel.

Passageways 55 are also provided in the block 12 and establish communication between the valve member 18 and atmosphere, through the passageways 25 and 29, therefore, should it be desired to operate the device in a neutral position, by turning the valve member 18 to a position as shown by Figure 5, air will be drawn into the valve member 18 on one stroke of the piston, and exhausted on the return stroke thereof.

Should it be desired to create a vacuum in the measuring vessel to draw blood into the vessel, the valve member 18 is moved to a position as shown by Figure 6, whereupon air is drawn through the upper passageway 13, through the valve 18, and exhausted through passageway 29. When a sufficient quantity of blood has been drawn into the measuring vessel, the valve 18 is operated to cause the groove 16 to register with the passageway 13 and groove 17 with passageway 25, as shown by Figure 7. The action of the piston 8 will now act to compress air in the measuring vessel to force blood therefrom.

From the foregoing it will be obvious that when the maximum vacuum has been produced in the vessel 44, the valve 39 will be lifted from its seat against the tension of the spring 40, relieving excessive vacuum.

When the maximum pressure has been pro-

duced in the vessel 44, the valve 37 will be raised against the tension of the spring 41' relieving excessive pressure within the vessel 44.

I claim:

- 5 1. A transfusion device comprising a base, a support mounted on the base, a measuring vessel mounted on the support, inlet and outlet tubes connected with the support, a valve for controlling the passage of liquid to and from the measuring vessel, a pump for creating a vacuum or pressure within the measuring vessel, a valve for controlling the passage of air to or from the measuring vessel to create a vacuum or pressure within the measuring vessel, and means for connecting the valves to operate simultaneously.
- 10 2. A transfusion device comprising a base, a support on the base, a measuring vessel mounted in the support, inlet and outlet tubes connected with the support, a valve for controlling the passage of liquid to and from the measuring vessel, a pump for creating a vacuum or pressure within the measuring tank, a valve for controlling the passage of air to and from the pump, and a link connecting the valves to move the valves simultaneously.
- 15 3. A transfusion device comprising a base, a support on the base, a measuring vessel mounted in the support, inlet and outlet tubes connected with the support, a valve for controlling the passage of liquid to and from the measuring vessel, a pump for creating a vacuum or pressure within the measuring vessel, a vacuum relief valve and a pressure relief valve in communication with the measuring vessel, a valve for controlling the passage of air to and from the pump, and a link connecting the first and last mentioned valves to move them simultaneously.
- 20 4. A transfusion device comprising a base, a support mounted on the base, a measuring vessel mounted on the support, inlet and outlet tubes connected with the support, a valve for controlling the passage of liquid to and from the measuring vessel, a pump for creating a vacuum or pressure within the measuring vessel, a vacuum relief valve and a pressure relief valve in communication with the measuring vessel, and a valve for controlling the passage of air to or from the measuring vessel to create a vacuum or pressure within the measuring vessel.
- 25 5. In testimony that I claim the foregoing as my own, I have hereto affixed my signature.

RALPH P. KIPP.
